UNITED STATES PATENT OFFICE.

CHARLES DE QUETTEVILLE WHITTLE, OF KENILWORTH, ILLINOIS, ASSIGNOR TO ALFRED VESTER SONS, INC., OF PROVIDENCE, RHODE ISLAND, A CORPORATION OF RHODE ISLAND.

DESIGN FOR A BANDING FOR LIGHTING FIXTURES.

Application filed February 17, 1926. Serial No. 16,554. Term of patent 7 years.

To all whom it may concern:

Be it known that I, CHARLES DE QUETTEVILLE WHITTLE, a citizen of the United States, residing at Kenilworth, in the county of Cook and State of Illinois, have invented a new, original, and ornamental Design for a Banding for Lighting Fixtures, of which the following is a specification, reference

being had to the accompanying drawing, forming part thereof, in which the figure is a section of banding, showing my new design.

I claim—

The ornamental design for a banding for lighting fixtures, as shown.

CHARLES de QUETTEVILLE WHITTLE.
